COMBINED PUMP AND SIPHON SYSTEM

Patrick Gavin, Brooklyn, N. Y.

Application April 24, 1943, Serial No. 484,410

5 Claims. (Cl. 103—1)

This invention relates generally to pumps and is adapted more particularly for use where large bodies of water or other liquid are adapted to be moved. While the invention is capable of a wide variety of uses, it is primarily designed for the pumping out of drydocks for this work should be carried out as expeditiously as possible and a large bulk of water should be moved to clear the drydock in a relatively short time.

The present invention is particularly appropriate for this use for it may be made in relatively large sizes to embody a pump with an exceptionally long stroke and with operating parts so constituted that they will not be apt to get out of order, nor be damaged by the presence of sand, grit or other extraneous matter.

Speaking generally, the invention comprises a relatively long cylinder, the opposite ends of which communicate with two inlet pipes, one end of each of which is adapted to be submerged into the liquid to be pumped, while beyond the cylinder the pipes are brought together to form a single discharge pipe. In each of these two pipes are inlet and outlet valves and, as a piston is reciprocated in the cylinder, these valves open and close automatically to provide a double action pump adapted to effect a substantially constant discharge of liquid through the single discharge pipe.

The piston may, if desired, traverse the entire length of the cylinder and is provided at its opposite ends with anchorages for cables. These cables pass from the piston to and about appropriate directional rollers to equalizers. The equalizers are connected by cables which pass over other directional rollers and are secured intermediate their ends to endless chains which operate in a continuous manner around spaced apart sprockets. These sprockets are driven from a suitable prime mover, so that, as the sprocket chains travel, they reciprocate the piston so that it can perform its pumping functions. As this piston is frequently made quite large and operates in a horizontal cylinder, I preferably mount the piston on wheels and these wheels ride on the wall of the cylinder and support the weight of the piston, so that undue wear is eliminated. This permits the piston to be formed with packing rings which are pneumatically maintained in contact with the cylinder wall and the pneumatic elements of the piston packing are so arranged that they may be inflated from the exterior of the cylinder and without dismantling the same. The invention also provides for the admission of lubricant in the same way. These considerations

are highly important from a practical standpoint for the pump may be serviced while it continues to operate.

An important feature of this invention consists in the fact that the system may be operated to pump liquid until the inlet and outlet pipes of the system are full and, if the outlet leg of the water column passing through the system is longer than the inlet leg, the pump may then be stopped and the system will operate to siphon off the liquid.

Features of the invention, other than those adverted to, will be apparent from the hereinafter detailed description and claims when read in conjunction with the accompanying drawings.

The accompanying drawings illustrate different practical embodiments of the invention, but the constructions therein shown are to be understood as illustrative, only, and not as defining the limits of the invention.

Figure 1 is a perspective view showing the system of the present invention.

Figure 2 is a fragmentary vertical section through one of the two inlet pipes, this section being taken in the plane of the line 2—2 of Figure 3.

Figure 3 is a section on the line 3—3 of Figure 2.

Figure 4 is a plan view of a clamp shown in section in Figure 3.

Figure 5 is a section on the line 5—5 of Figure 6 and shows a float controlled valve in elevation.

Figure 6 is a section on the line 6—6 of Figure 5.

Figure 7 is a vertical section through the cylinder and piston therein and through the two inlet pipes and boxes at the opposite ends of said cylinder.

Figure 8 is a section on the line 8—8 of Figure 7.

Figure 9 is a section on the line 9—9 of Figure 7.

Figure 10 is a fragmentary section of one end of the assembly shown in Figure 7, but illustrating a modified form of construction.

Referring to the drawings, 1 and 1' designate a pair of inlet pipes which are adapted to project into the pool P of liquid to be pumped and project upwardly therefrom in substantially vertical parallel relation for a distance and thereupon extend horizontally as indicated at 2 and 2' for a distance in parallel relation and the pipe 2' is thereupon deflected in the direction of the pipe 2 to join the same, so that both of these pipes may feed a single discharge pipe 3, shown as extending over the wall 4 of a drydock and downwardly to an appreciable distance exteriorly of said wall. The pipes 1, 1', 2 and 2' thus constitute

55 twin inlet pipes feeding a single or common ex-

haust pipe 3. Between the parallel portions 2 and 2' of the twin inlet pipes extends a pump cylinder 5. This pump cylinder is preferably of somewhat less diameter than the portions 2 and 2' of the inlet pipes and intersects these inlet pipes as shown in Figures 3 and 7. Opposite the ends of the cylinder the inlet pipes are provided with openings closed by end plates 6 and 6' secured in place with gaskets, so as to preclude leakage and to the exterior of these end plates are secured upright boxes 7 and 7'. Near the bottom of each of these boxes is a directional roll 8, 8' and juxtaposed with each of these rolls the end plates 6, 6' and the boxes 7, 7' are perforated for the passage of a cable.

Positioned within the cylinder 5 is a piston 9, shown in detail in Figures 7, 8 and 9 and presently described. To the opposite ends of this piston are secured cables 10 and 10'. These cables extend through the perforations in the end plates 6 and 6', thence pass around the directional rolls 8 and 8' and thence extend upwardly through the tops of the boxes 7 and 7' and are secured to equalizers 11 and 11'. To these equalizers are secured the ends of two cables 12 and 13 which pass over directional rollers 14 and between these rollers, these cables are secured to anchorages 15 attached to sprocket chains 16. These sprocket chains 16 are passed about spaced sprockets 17 and are adapted to be driven through a drive gear 18 which is, in turn, driven by a pinion 19 from any suitable prime mover.

The directional rollers 14 are shown below the sprockets 17 although they may be positioned at any points desired depending on conditions. The parts are so arranged that, as the sprocket chains 16 travel, they carry the anchorages 15 with them and thus alternately take up and play out the cables 10 and 10', which are secured to the opposite ends of the piston and thus impart reciprocation to the piston 9 within the cylinder 5.

Inlet valves 20 and 20' are positioned within the twin inlet pipes 2 and 2', while outlet valves 21 and 21' are positioned at the other side of the cylinder, so that when the piston is reciprocated as described, liquid will be drawn from the pool P alternately through the inlet valves 20 and 20' and alternately discharged through the valves 21 and 21' and through the common discharge pipe 3.

A pronounced advantage with this type of drive for the piston is that the stroke of the piston can be very long because the sprockets 17 can be spaced apart at any convenient distance and it is this spacing of the sprockets that controls the throw of the piston. As the piston travels back and forth, it draws in a large charge in moving in one direction, while it is ejecting a large charge, and vice versa, so that by this double action operation a substantially constant flow of liquid is fed to and through the discharge pipe 3. It will of course be understood that the inlet and outlet valves, 20, 20' and 21 and 21' function to permit passage of liquid in the direction of discharge and automatically close to prevent any retrograde flow of the liquid.

The valves may differ in type, but one satisfactory type of valve is illustrated in Figure 2. Its pivot 22 floats within a socket 23, while the valve is set on a 45 degree seat 24, so that it functions as a check valve to allow the passage of liquid in only one direction. A manually operable valve opening member 25 may extend into accessible position to open the valve by hand when

desired to permit retrograde flow of the liquid, as when it is desired to drain the system or to facilitate the use of the system as a siphon. All the valves referred to are of the same type of quick opening valve set into pipes 2 and 2' which are of a larger diameter than the pipes 1, 1' or 3, so as not to impede the flow of liquid and to permit slight opening of the valve to pass liquid in large volume.

10 In operating this system, it is possible that the pipes 1, 1', 2 and 2' be completely submerged in the pool P. In this case the boxes 7 and 7' may be omitted, as shown in Figure 10, because leakage of water through the opening in the end plates 6, 6', will not interfere with the proper syphoning operation of the system if these openings are submerged. However, when the major portion of the system is operated above the surface of the pool as in Figure 1, the use of the boxes 7 and 7' is preferred to eliminate this leakage, particularly if the advantages of the use of the system as a siphon is desired, for by these boxes the leakage of air with consequent breaking of the suction or separation of the siphon column is precluded.

15 When the system is operating as a siphon, as will be presently described, the top of the box is sealed as shown in Figure 3. In order to permit of this sealing, each of the cables 10 and 10' has incorporated therein an elongated cylindrical portion 26, which, when the piston is midway of its stroke, projects partially into and partially above the top of each box. When in this position, a sealing block 27 resting on a gasket 28 on the top of the box is adapted to closely surround the enlargement 26 of the cable. This block 27 carries a packing 29 and an adjusting packing gland 30 is adapted to be forced down on the packing to form a tight joint and hermetically seal the top end of the box 7. However, when the pump is to function as a pump the block 27 and gland 30 are adapted to be released and lifted up above the top of the enlargement 26 and held in this position by means of a clamp 32 clamped around the cable 10, as indicated in dotted lines in Figure 3. The plan view of this clamp is shown in Figure 4.

20 Near the top of the box is an outlet 33 controlled by a valve 34 and leading back to the pool P. This is an overflow or level regulating outlet, so that the box may be normally kept filled with liquid up to this point. Also near the top of the box a pipe 35 leads to the delivery pipe 3, so that liquid can flow from the pipe 3 into the box 7, as hereinafter described. This flow of liquid is controlled by a float valve 36, the details of which are shown in Figures 5 and 6. In these views, the valve itself bears the reference character 36, while its controlling float is designated 37. The float is shaped to fit about the enlargement 26 on the cable.

25 When the pump is operating, the valve 36 is normally closed, while the valve 34 is left open. The pump operates to pump water from the pool P over the wall 4 and to discharge it exteriorly of the wall. A valve 38 at the lower end of the outlet pipe is allowed to open by releasing its closing cable 39 and the pump functions as a double action pump to feed water from the pool over the top of the wall. During this normal operation, the box 7, as well as the companion box 7' at the other end of the cylinder, are unsealed at their tops and water which leaks into the bottom of the box through the relatively small opening around the cable will tend to fill up the

box, while water will flow back through the pipe 35 to augment this supply until the box fills up sufficiently so that the float valve 36 will close it off. The liquid is kept from overflowing from the top of the box by its passage through the overflow 33.

Now in the event that the outlet leg of the pump is longer than the inlet leg, it is possible, when the system is filled, to employ it as a syphon. This is accomplished in the following manner. The piston is brought to rest midway of the length of the cylinder. The tops of the boxes 7 and 7' are sealed as shown in Figure 3. The valve 34 is closed, so that air cannot get into the system and the valve operating members 25 are manually operated to open the valves 20, 20', 21 and 21'. This will permit an unobstructed flow of water from pool P, through the closed syphon over the top of the wall 4 to the outside thereof, until the pool P has been exhausted or until the level outside of the wall substantially equals the level of the pool P. In the latter case the syphon will discontinue as these levels approach one another and the pump must be started up if further water is to be pumped from the pool over the wall.

A very important practical feature of the present invention is that close tolerances or nice fitting is not required. Slight leakages here and there are not important for the volume of the liquid handled will not be seriously affected by such leakages. In fact it is possible to build up practically the whole piping system by welding together metal tubing. The only fairly smooth operation that is required is the interior of the cylinder wall which should be smooth and fairly true. The other parts of the piping may be rough tubing and by welding it together as described an assembly of relatively large tubing for a pump of large capacity will weigh comparatively little and can be handled conveniently. It can be swung into place by a crane or it can form a permanent assemblage on a tug, lighter, or other vessel, or from a permanent adjunct to a drydock, dam or other installation, where the transportation of the liquid is required.

The drive mechanism may be mounted, if desired, some distance from the tubular portions of the system and the cables 10 and 10' may be quite long and may be led around directional rolls to the piston. It is of course possible to connect the opposite ends of the cables 10 and 10' directly to one of the sprocket chains 16 and thus drive these cables from only one sprocket chain, but I have shown a dual drive with equalizers, so as to eliminate undue torque on the shafts on which the drive sprockets are mounted. This, however, is optional.

In a large capacity pump of the kind described, the piston will be quite large and as it works in the horizontal cylinder 5, it would, under normal conditions, tend to produce excess wear on the lower portion of the cylinder and packing. For this reason, I preferably provide rollers 40 on which the cylinder can ride and thus eliminate undue wear. The piston construction is shown best in Figures 7, 8 and 9. Here said piston is shown as built up of from four disks 41, 42, 43 and 44 spaced apart by spacers 45 and clamped together against the spacers by a core spindle 46, one end of which is threaded to receive a nut 47 by which the clamping action is produced. Between the outer spacers 45 and the wall of the cylinder are positioned circular pneumatic tubes 48 similar to the inner tube of an automobile tire. The 75

inner peripheries of these tubes are seated in annular saddles 49, while the outer peripheries of the tubes bear against resilient packing rings 50. To permit of inflation of the tubes 48, the nipples are connected to a common inflation pipe 51 which extends through the end plate 6 and at the exterior of which is positioned a valve inflation nipple 52, so that the pneumatic tubes can be pumped up from the exterior of the apparatus. The inflation pipe 51 is long enough to permit of the full stroke of the piston without placing a strain on the pipe and it is passed at intervals through rings 53 supported on the cable 10', so that, as the piston moves to the left in Figure 7, the inflation pipe will drape itself into loops. The inflation pipe is preferably secured to the rings to maintain proper spacing. By thus keeping the tubes 48 inflated, the packings 50 will be forced resiliently against the cylinder wall to have a nice sliding fit therewith without undue leakage.

The piston is of the dual type with two packing rings and two pneumatic tubes. The two central plates 43 and 44 are spaced apart to provide a lubricating space between them and lubricant can be fed to this space through a lubricating pipe 54 which leads through the end plate 6 in the same manner as described with reference to the inflation pipe. The lubricating pipe 54 is also supported by rings 55, to loop as shown.

Thus air may be fed to the piston tubes from one side of the system while lubricant may be fed to the piston from the other side, both without stopping the apparatus or dismantling any part thereof.

While the lubricant is being initially introduced into the lubricating chamber through the lubricating pipe 54, residual air in said chamber should be vented. For this purpose I provide a vent valve 56 located centrally of the length of the cylinder and if the piston is brought into registration with this valve lubricant can then be introduced into the lubricating chamber between the rings until the chamber is filled while residual air in said chamber will be exhausted through the vent 56. After the chamber is filled, the vent valve 56 is closed.

Directly below the vent valve 56 is a drain valve 57 so that when desired the piston may be brought into registration therewith and the valve 57 opened so that the lubricant in the lubricating chamber may be drawn off.

The rollers 40 to which I have referred may be in any desired number, but three are shown as illustrative. They are mounted on the disks 41 and 44 and serve to carry the weight of the piston so that such weight is not carried by the packing rings as is generally the case in horizontal pumps.

It will be noted from Figure 1 that at the uppermost part of the outlet pipe 3 a vent valve 58 is provided and air can be allowed to escape from the pipe 3 through this valve. In practice, the method of operating this valve is as follows: The operation of the pump is started while the valve 38 at the outlet end of the pipe 3 is kept closed while the valve 58 is opened and this condition exists until the entire outlet pipe 3 is filled and until water starts to come through the vent valve 58. The operator then knows that the outlet pipe 3 is completely filled. He then closes the valve 58 while he operates the control line 39 to open the valve 38 and from then on the liquid flows through the pipe 3 in

an uninterrupted stream and without air pockets therein, so that in the event it be later desired to operate the system as a siphon there will be no air pockets in the system which would preclude its proper functioning in this connection.

In the accompanying drawings I have shown two inlet pipes 1 and 1' and a single outlet pipe 3. In practice it is entirely practical to connect the pipes 1 and 1' together at their lower ends to form a single inlet pipe. This and other changes can be made without departing from this invention.

The foregoing detailed description sets forth the invention in its preferred practical forms, but the invention is to be understood as fully commensurate with the appended claims.

Having thus fully described the invention, what I claim as new and desire to secure by Letters Patent is:

1. A system of the character described comprising a pair of inlet pipes spaced apart and connected to a common exhaust pipe, said pipes constituting inlet and exhaust legs of the system, a cylinder extending between the spaced inlet pipes and having therein a piston, cables secured to the opposite ends of the piston and which cables are also secured to power operated means to alternately take up on each cable as the other cable is played out for the purpose of reciprocating the piston in said cylinder, inlet and discharge valves positioned in the inlet pipes to supply liquid to the cylinder and to discharge the liquid from the cylinder, said cables passing through liquid traps beyond the opposite ends of the cylinder to seal the system against the entrance of air, whereby the system may be used to siphon water when the descending liquid column in the exhaust leg is longer than the ascending liquid column in the inlet leg, and means for holding said inlet and exhaust valves unseated during such water siphoning.

2. A system of the character described comprising a pair of inlet pipes spaced apart and connected to a common exhaust pipe, said pipes constituting inlet and exhaust legs of the system, a cylinder extending between the spaced inlet pipes and having therein a piston, cables secured to the opposite ends of the piston and which cables are also secured to power operated means to alternately take up on each cable as the other cable is played out for the purpose of reciprocating the piston in said cylinder, inlet and discharge valves positioned in the inlet pipes to supply liquid to the cylinder and to discharge the liquid from the cylinder, said cables passing through liquid traps beyond the opposite ends of the cylinder to seal the system against the entrance of air, whereby the system may be used to siphon water when the descending liquid column in the exhaust leg is longer than the ascending liquid column in the inlet leg, means for holding said inlet and exhaust valves unseated during such water siphoning, and a liquid feeding duct extending from the pressure side of the system to the liquid traps to maintain the liquid in said traps at a substantially uniform level.

3. A system of the character described comprising a horizontal cylinder, a pair of inlet pipes leading from a pool of liquid adapted to be pumped to the opposite ends of said cylinder,

5 der, a pair of outlet pipes leading from the opposite ends of the cylinder to and uniting to form a common outlet pipe, a piston in said cylinder, directional rollers positioned adjacent the ends of said cylinder and exteriorly of the pipes with which the cylinder joins, cables secured to the opposite ends of said piston and extending to and about said directional rollers and thence to power operated means to alternately take up on each cable as the other cable is played out to impart reciprocation to the piston, inlet valves in said inlet pipes, outlet valves in said outlet pipes, and liquid trap boxes enclosing said directional rollers and extending upwardly to provide space therein for liquid traps to form liquid seals to the system where the cables pass from the cylinder to the directional rollers, and means for maintaining a substantially uniform liquid level in the liquid trap boxes.

20 4. A system of the character described comprising a horizontal cylinder, a pair of inlet pipes leading from a pool of liquid adapted to be pumped to the opposite ends of said cylinder, a pair of outlet pipes leading from the opposite 25 ends of the cylinder to and uniting to form a common outlet pipe, said inlet and outlet pipes constituting inlet and outlet legs of the system, a piston in said cylinder, directional rollers positioned adjacent the ends of said cylinder and exteriorly of the pipes with which the cylinder joins, cables secured to the opposite ends of said piston and extending to and about said directional rollers and thence to power operated means to alternately take up on each cable as the other cable is played out to impart reciprocation to the piston, inlet valves in said inlet pipes, outlet valves in said outlet pipes, liquid trap boxes enclosing said directional rollers and extending upwardly to provide space therein for liquid traps to form liquid seals to the system where the cables pass from the cylinder to the directional rollers, means for maintaining a substantially uniform liquid level in the liquid trap boxes, the upper ends of the liquid trap boxes being normally open when the piston is in operation, means for sealing the upper ends of said liquid trap boxes about the cables to permit the system to operate to siphon liquid when the descending liquid column in the outlet leg is longer than the ascending liquid column in the inlet leg of the system, and means for holding said inlet and exhaust valves unseated during such water siphoning.

50 5. A siphon system comprising a siphon tube having an ascending inlet leg connected at its upper end to the upper end of a descending outlet leg at the apex of the siphon tube, a pump connected to said inlet leg to pump liquid into the siphon tube to fill the same, sealing means to seal the lower end of the outlet leg until both legs are filled with liquid through operation of the pump, with means at the apex of the siphon tube to vent said tube to the atmosphere and cause residual air in the siphon tube to be exhausted to the atmosphere as said tube is filled with liquid by the pump, and means for bypassing the pump when the siphon tube is thus filled, whereby the system may then operate as a siphon system upon operation of said sealing 60 means to unseal the lower end of said outlet leg.

PATRICK GAVIN.
